ELECTRICAL CONNECTOR

Morris E. Wood, Newbury, Mass., assignor to The Chase - Shawmut Company, Newburyport, Mass., a corporation of Massachusetts

Application January 29, 1941, Serial No. 376,444

2 Claims. (Cl. 173—259)

This invention relates to electrical connectors particularly adapted although not necessarily limited to connecting the terminal of an electric fuse base with the circuit conductor.

The design of a connector for the above purpose presents difficult problems. The fuse develops heat which to a considerable extent is passed through the connector and into the conductor where it is dissipated. A solder type of connector can have its solder melted by the heat. Certain types of solderless connectors wherein a clamping screw is used to provide electrical connection can become loose under repeated heating and cooling of the fuse under load variations. A loose connector generates heat which passes into the fuse and can result in its premature operation.

Hence an object of the present invention is the provision of an improved form of solderless connector free from the above enumerated troubles.

Electric fuses are commonly arranged in close side by side order on a base and within a metal enclosure. The permissible spacing of the fuses is determined by the distance between the exposed conducting metal parts of the fuse circuits. Some connectors are relatively wide and hence necessitate a detrimentally relatively wide spacing of the fuses.

It is an object of the present invention to provide an improved form of connector that is narrow so that the closeness of the spacing between adjacent fuses is not governed by the connector.

The connector of the present invention is particularly intended to connect a stranded cable, composed of a bundle of small conductors, to a terminal. The current carrying capacity of a stranded cable depends upon the capacity of the individual conductor or strand of the cable. If the connector for such a cable is such that contact is made directly with but a few strands then the current of the other strands must pass through these strands and overload and hence heat them. Thus, for a stranded conductor it is important that the connector engage the individual strands as directly as possible, especially when used with an electric fuse. Thus, an object of the present invention is the provision of an improved form of electric connector wherein the clamping pressure spreads the strands of the cable and the parts of the connector are so constructed and arranged to make a more direct contact than heretofore with the individual strands.

A more specific object of the invention is to combine in one connector a high clamping pres-

sure by the use of two clamping screws, and a large clamping extent by using the sides of the screws to engage many of the individual strands of the conductor, the threads of which screws engage and hold the contacting strands of the conductor.

Another object of the present invention is to provide an electrical connector wherein one of the clamping members is arranged to be flexed under clamping pressure, thus producing a contact between the conductor and the connector that is positive under all conditions of use.

A further object of the invention is to provide a connector member particularly adapted for use in connection with fuse cut-out bases and stranded conductors, wherein the connector is positioned between two clamping members and in engagement therewith when clamping pressure is applied, thus forcing the connector to spread apart the free end portions of the strands of the conductor to such an extent that it cannot be pulled out of the connector.

A still further object of the invention is to improve generally upon the construction and operation of electrical connectors.

With the above and other objects and features in view, the invention will now be described with reference to the accompanying drawing in which:

Fig. 1 is a plan view of a fuse cut-out base having portions thereof cut away to illustrate the construction of the connector members;

Fig. 2 is a view in cross-section taken along the line 2—2 of Fig. 1;

Fig. 3 is a view in cross-section taken along the line 3—3 of Fig. 1 prior to applying clamping pressure to the conductor;

Fig. 4 is a detail view of the connector similar to the one illustrated in Fig. 3 but showing the parts of the connector in clamping position;

Fig. 5 is a view similar to Fig. 3 but illustrating a small conductor in position to be clamped by the connector;

Fig. 6 is a view similar to Fig. 4 but showing a small conductor of Fig. 5 clamped in the connector;

Fig. 7 is an exploded view illustrating the present connector;

Fig. 8 is a bottom plan view of the top clamping plate of the present invention; and

Fig. 9 is a view in cross-section on a somewhat enlarged scale taken along the line 9—9 of Fig. 8.

The present invention is illustrated as embodied in a fuse cut-out base of the usual construction. As illustrated, the cut-out base 10 is formed of ceramic material such, for example, as

porcelain and is provided with upstanding partition members 12 for separating the terminal connectors 14 to prevent arcing therebetween. The illustrated cut-out base is arranged to receive two ferrule type cartridge fuses 15. Since each of these cartridge receiving terminals are identical it will be necessary to describe only one terminal and connector in detail herein.

Referring now to Figs. 2 and 3 of the drawing, it will be noted that the cut-out base 10 is provided with a recess 16 for receiving the connector and the spring clip fuse terminal 14. The spring clip terminal 14 is formed in the usual manner with a flat intermediate base portion 18 and two arcuate side walls 19, spring-urged toward each other for receiving and clamping the end terminal 15a of a ferrule-type cartridge fuse.

The connector 20 is provided with a base plate 22 having a left hand end portion 21 which is arranged to bear against the surface of the recess 16 and with a slightly offset higher parallel portion 22 which is arranged to bear against the upper face of the intermediate or base portion of the fuse clip 14. The base member 22 and the clip 14 are fixed to the base by a bolt 24 which passes through openings in the base 20 and in the spring clip 14, the parts being held in clamping position by a nut 26 which is threaded onto the lower end of the bolt 24. It is to be noted that the base portion 13 of the fuse clip 14 is of substantially the same width as the recess 16 and hence the spring clip 14 is prevented from substantial turning movement about the bolt 24. The end 22 of the base 20 is substantially of the same width as the inside of the spring fuse clip 14. Thus, turning movement of the base 20 therein is prevented. The left hand end 21 of the base 20, as shown most clearly in the left hand portion of Fig. 1, is of substantially the same width as the recess, thus further preventing any relative rotational movement between the parts. The horizontal width of the part 21 also is not materially greater than the width of the fuse clip.

The left hand end 21 of the base 20 is provided with a pair of spaced threaded openings 28 in which parallel clamping screws 30 are screw-threaded. It is to be noted that the base 10 is provided with openings 32 for receiving the lower ends of the clamping screws 30.

The connector is provided with a steel clamping plate 34 having spaced openings 36 loosely receiving the screws 30. The distance between the openings 28 or the openings 36 is just slightly greater than the diameter of the largest conductor which is to be used with the connector. Thus, as illustrated in Figs. 2 and 3, the conductor 38, which is stranded, occupies substantially the entire space between the clamping screws 30. Thus, when pressure is applied the conductor 38 is distorted as shown in Fig. 4 and occupies the entire area between and contacts with the base 20, the plate 34, and the clamping screws 30 and the screw threads thereof. Thus, good contact is assured between the conductor and the base 20. Furthermore, the clamping pressure is great enough to bend or flex the clamping plate 34. Thus, the conductor 38 is resiliently held against the connector base 20 so that good electrical contact is insured between the base 20 and the connector 33 under all conditions of expansion and contraction of the screws 30 in response to temperature variations, the plate acting as a lock washer to prevent the screws from becoming loose. Furthermore, the strands 39 of the conductor 38 are forced against the clamping screws

30 with substantial force so that good contact is made. The friction between the strands of the conductor 38 and the screws 30 is sufficient to prevent unintentional turning of the screws in an unclamping direction. The clamping pressure, as described just above, is sufficient to cause the strands of the conductor 38 at its free end to fan or flare outwardly, as shown most clearly in the upper right hand portion of Fig. 1 at 41, thus preventing the conductor from being pulled lengthwise out of the connector. In order further to insure that the conductor will not be pulled out of the connector, the clamping plate 34 at its bottom surface, as shown most clearly in Figs. 8 and 9, is provided with a series of serrations or teeth 40 which extend transversely of the conductor and which bite into the strands of the conductor 38 in clamping engagement therewith, thus additionally preventing lengthwise movement of the conductor 38.

While the present construction is particularly well adapted for large conductors, such as shown in Figs. 2, 3 and 4, the connector is equally effective with stranded conductors 42 of smaller size. It will be noted that, in Fig. 5 before clamping pressure is applied thereto, the conductor 42 has a diameter which is substantially less than the distance between the clamping screws 30. However, when clamping pressure is applied thereto the strands of the conductor 42 will spread sideways and occupy the entire space between the screws 30, the clamping plate 34 and the connector base 20. Thus, with the smaller conductor 42 effective electrical connection between the connector base 20 and the end of the connector 42 is provided. The flattening of the conductor 42 also spreads or flares the free end thereof as shown in the upper part of Fig. 1 so that lengthwise movement of the conductor is prevented. Also the plate 34, having the serrations or teeth 40 thereon, further prevents longitudinal movement. Thus, it is apparent that the connector member is fully as effective for a small stranded conductor as it is for a large stranded conductor.

It is to be understood that while the connector described above is adapted effectively to clamp conductors of varying sizes, it is not intended that only one size of connector shall be used for all sizes of stranded electrical conductors but to use a different size of connector for each different size of fuse terminal. Thus, each size of connector will be particularly effective upon all different sizes of wire properly used with any particular size of fuse terminal.

It is to be noted that by having the strands of the conductor directly engage the clamping screws a large extent of contacting surface is provided, much greater than the usual cylindrical clamping recess frequently provided and the transverse width of the connector is small so that the fuses can be close together without impairment of the strike-over distance between them.

Having thus described my invention, what I claim as new and desire to secure by Letters Patent of the United States is:

1. An electric connector comprising in combination with a bared end of a stranded conductor normally substantially circular in cross section and having the strands relatively movable, a pair of opposed substantially flat-faced clamp plates one of which is connected with a part to be conductively connected, a pair of spaced clamp screws passed through and connected electrically with said plates and spaced 75 apart by a distance not materially greater than

necessary to admit the diameter of the end of the stranded conductor to be clamped, the confronting faces of said plates with said screws defining the boundaries of a rectangular conductor-receiving space into which the end of the stranded conductor is inserted and said screws being tightened down to bring the flat faces of said clamp plates forcibly against opposite sides of the stranded portion of the conductor thereby forcing the strand portions of the bared end out of circular arrangement and rearranging the strands into a substantially rectangular cross section engaged on the four sides by said plates and said clamp screws and with the ends of the strands substantially fanned out laterally to a greater collective width than the width between said clamp screws thus jamming the strands against the screws and preventing endwise displacement and pulling out of the conductor from between said screws and said clamp plates.

2. An electric connector comprising in combination with a bared end of a stranded conductor normally substantially cylindrical and having the strands relatively movable, a pair of opposed substantially flat-faced clamp plates one of which is connected with a part to be conductively connected, a pair of spaced clamp screws passed through said plates and spaced apart by a distance not materially greater than necessary

5 to admit the diameter of the cylindrical end of the stranded conductor to be clamped, the confronting faces of said plates with said screws defining the boundaries of a substantially rectangular conductor-receiving space into which the end of the stranded cylindrical portion of the conductor is inserted and said screws being tightened down to clamp said clamp plates forcibly against top and bottom sides of the stranded portion of the conductor thereby forcing the strand portions of the bared end out of circular arrangement and rearranging the strands into a substantially rectangular cross section conductively contacted and engaged on the four sides by said plates and said clamp screws and with the ends of the strands substantially fanned out laterally to a greater collective width than the width between said clamp screws thus preventing endwise displacement and pulling out
10 15
20 25 of the conductor from between said screws and said clamp plates, one of said clamp plates being resilient and flexing under clamping pressure of said screws and engagement with the conductor thereby maintaining clamping pressure upon the stranded conductor in contact with the threaded sides of the clamping screws and substantially frictionally locking said screws against loosening.
